UNITED STATES PATENT OFFICE.

RICHARD M. ATWATER, OF MILLVILLE, NEW JERSEY, ASSIGNOR TO JAMES WHITALL, JOHN M. WHITALL, AND J. WHITALL NICHOLSON, OF PHILADELPHIA, PENNSYLVANIA, C. ALBERT TATUM AND FRANCIS M. UNDERHILL, OF NEW YORK, N. Y., AND JOHN MICKLE, OF MILLVILLE, NEW JERSEY.

DESIGN FOR A BOTTLE.

SPECIFICATION forming part of Design No. 18,221, dated April 3, 1888.

Application filed March 10, 1888. Serial No. 266,905. Term of patent 14 years.

To all whom it may concern:

Be it known that I, RICHARD M. ATWATER, a citizen of the United States, and a resident of Millville, Cumberland county, New Jersey, have invented a new and original Design for a Bottle, of which the following is a specification.

My design for a prescription-bottle is fully illustrated in the accompanying drawings, in which—

Figure 1 is a perspective view of the bottle. Fig. 2 is a side view. Fig. 3 is a longitudinal section on the line 1 2, Fig. 2; and Fig. 4 is a sectional plan on the line 3 4, Fig. 2.

The body *A* of the bottle is of general quadrangular shape in cross-section, but has the corners beveled, by preference, as shown in Fig. 4, and has vertical-sides *a*, with rounded shoulders *b* at the top, merging into the neck *d*.

At the junction of one of the sides *a* and one of the shoulders *b* is a tablet, *e*, circular or

oval in form and inclined in respect to the side of the bottle, part of the tablet being on the side and part on the shoulder of the bottle. The tablet is preferably surrounded by a continuous raised rim. 25

I claim—

The herein-described design for a bottle, said design consisting of the body of general quadrangular shape in cross-section, and having vertical sides with shoulders at the top, and at one side an inclined tablet, partly on the shoulder and partly on the side of the bottle, all substantially as shown and described. 30

In testimony whereof I have signed my name 35 to this specification in the presence of two subscribing witnesses.

RICHARD M. ATWATER.
